TELESCOPING TRAVERSE ROD

Harry S. Rosenbaum, Baltimore, Md., assignor to Eastern Products Corporation, Baltimore, Md., a corporation of Maryland

Filed Apr. 16, 1965, Ser. No. 84,816

Term of patent 14 years

(Cl. D21—1)

FIG. 3

FIG. 5

FIG. 1

FIG. 4

FIG. 2

FIG. 1 is a front perspective view of a telescoping traverse rod showing my new design, portions thereof are shown broken away to indicate indeterminate or indefinite length;

FIG. 2 is an enlarged cross-sectional view taken along the line 2—2 of FIG. 1;

FIG. 3 is a rear view of the telescoping traverse rod of FIG. 1;

FIG. 4 is an enlarged perspective view of a portion of the traverse rod of FIG. 1; and

FIG. 5 is an enlarged front elevational view of the right hand end housing of FIG. 1.

I claim:

The ornamental design for a telescoping traverse rod, as shown and described.
